C. W. MACDONALD,
LOOSE LEAF BINDER,
APPLICATION FILED JAN. 12, 1921.

1,408,817.

Patented Mar. 7, 1922.

Inventor
Charles W. Macdonald

By his Attorney James Block

UNITED STATES PATENT OFFICE.

CHARLES W. MACDONALD, OF NEW YORK, N. Y.

LOOSE-LEAF BINDER.

1,408,817.

Specification of Letters Patent.

Patented Mar. 7, 1922.

Application filed January 12, 1921. Serial No. 436,655.

To all whom it may concern:

Be it known that I, CHARLES W. MACDONALD, a citizen of the United States of America, residing at New York city, county 5 and State of New York, have invented certain new and useful Improvements in Loose-Leaf Binders, of which the following is a full, clear, and exact description:

This invention relates to improvements in 10 loose leaf binding devices, one of the objects being to provide simple and inexpensive means to secure a plurality of loose leaves together, in book form, between covers if desirable, a further object of my invention being to provide a binding means arranged to engage folded pages, or in other words, paged printed matter as it comes from the press. Printing presses usually turn out the pages of a book in couples or 15 groups, which are folded by the press after having been printed. Instead of perforating these pages, as is usual when they are intended for loose leaf assembly, I provide means in the form of a bar to engage the leaves at the point where they are folded, the engaging means being slipped into place and not in any way fastened to the leaves. In combination with the leaf-engaging members, I provide a device to receive the 20 engaging members, after they have been inserted between the leaves formed by folded sheets of printed matter. As many folded sheets can be carried by one bar as may be desired. A book will be made up of a plurality of groups of leaves, each group having associated therewith a supporting bar, 25 all of said bars being retained by a support which is common to all.

I will now proceed to describe in detail 30 the manner of carrying out my invention, reference being had to the accompanying drawing, wherein:

Fig. 1 is a side elevation of a book made up in accordance with my invention; 35 Fig. 2 is a perspective detail view, illustrating a number of nested sheets and a retaining or locking bar associated therewith;

Fig. 3 is a perspective view of the supporting member for the bars and the thereby 40 carried sheets;

Fig. 4 is a fragmentary sectional plan view of an assembled book, the section being taken on a line 4—4 in Fig. 1;

Fig. 5 is a vertical sectional view, broken

away, the section being taken on a line 5—5 in Fig. 6;

Fig. 6 is a fragmentary longitudinal sectional view, the section being taken on a line 6—6 in Fig. 5;

Fig. 7 is a fragmentary perspective view 60 of the fly leaf member of a book assembly; and

Fig. 8 is a fragmentary view, illustrating the latching element for the leaves after they have been applied to the support for 65 the bars associated therewith.

As herein embodied, my invention consists of a supporting member 9, preferably struck out of sheet metal, having a channel 10 at one end and open at the top as at 11, and a channel 12 closed at the top as indicated by 13. The supporting member 9 further consists of a back member 9^a, a bottom member 14 and a latch 15 pivoted as at 16 to the back member 9^a. The end channels 11 and 12 will be 70 formed by the end walls 17 and flanges 18 carried thereby, said flanges being directed toward each other. The supporting member 9 will, as has been stated, be preferably struck from a single sheet of material. 80

To cooperate with the supporting member 9, I provide locking bars 19 arranged to be slipped between two sheets 20 and 21 and to rest within the fold thereof. As many similar sheets may be superimposed 85 upon sheets 20 and 21 as may be desired, as indicated in Fig. 2. The nested sheets will be held between the covers 22 and 23 of a book by means of the locking bars 19, as is evident. 90

It will be seen that the length of the bars 19 is somewhat greater than the width of the sheets, thereby providing projecting ends which are designed to enter the channels 11 and 12 whereby the bars and the 95 sheets carried thereby will be held in place against movement longitudinally of the book. To prevent the leaves and the bars 19 from being prematurely lifted out of the channels, I cover the channel 12 with the 100 plate 13 and provide the latch or pivoted cover 15 for the channel 11, which, after all of the bars have been inserted in the channel, is moved over to cover the adjacent projecting ends of the bars 19, as can be seen in 105 Fig. 5. To insert the bars, they will be slightly tilted, as indicated by dotted lines in Fig. 3, and one end thereof placed into

channel 12, after which said bars will be lowered to a horizontal position to cause the opposite end to enter channel 11.

In combination with bars 19 and support 9, I employ a support for a fly-leaf member 25, said support being of angular formation and indicated by 26 in Figs. 6 and 7. To apply the fly leaf to the book assembly, the angular supporting bar will be applied by having one of its walls inserted between the back-plate 9^a of the support 9 and uppermost group or groups of nested printed leaves. The angular bar will, of course, at one end, be inserted under plate 13, the opposite end being held down by the latch or cover 15. As can be seen in Fig. 7, the fly leaf 25 will at one end be secured to its angular supporting or locking bar 26. To finish off the back of the book, I provide the leaf supporting element 9 with a backing 27 of wood or other material to shape the back portion 28 of the book, or I may arrange the back plate 9^a of the support 9 to suitably support the portion 28 of the cover. After the bars 19 and leaves carried thereby have been placed in the support, the back plate 9^a of the support 9 will cooperate with the bars 19 to maintain the leaves in position; that is to say, the plate 9^a prevents movement of the leaves in one direction and the bars 19 in the other direction.

Having described my invention, what I

claim and desire to secure by Letters Patent is:—

1. In a loose leaf binder, a bar to retain a plurality of folded leaves, a support for said bar, having a channel at one end and closed at the top thereof to receive one end of said bar, a channel at the opposite end of said support open at the top thereof, and a cover arranged to be moved over the top of the channel having the open top to lock the said bar in position in said open ended channel.

2. A book, comprising a plurality of groups of nested leaves, the leaves of each group being inserted one within the other, a supporting bar passing through each group and projecting at each end beyond its group, a support for said bars consisting of a plate, a channel at each end thereof to receive the projecting ends of the bars, one of said channels being closed at the top and the other channel open at the top, a latch pivotally connected to the open channel, and a lip carried by the latch arranged to cover the open end of its channel to lock the bars in the support therefor.

Signed at New York city, N. Y., this 10 day of January, 1921.

CHARLES W. MACDONALD.
